UNITED STATES PATENT OFFICE.

ADAM A. VEEBELUNAS, OF MUNHALL, PENNSYLVANIA.

STRUCTURAL FORM.

1,190,824.

Specification of Letters Patent. Patented July 11, 1916.

Application filed February 4, 1915. Serial No. 6,057.

To all whom it may concern:

Be it known that I, ADAM A. VEEBELUNAS, a citizen of the United States, residing at Munhall, in the county of Allegheny and State of Pennsylvania, have invented a new and useful Improvement in Structural Forms, of which the following is a specification.

My invention relates to structural metal shapes such as beams, channels, angles, plates and other forms and more particularly to forming such metal with an integral conduit or pipe for various uses.

The object of my invention is to provide a cheap, simple and efficient form of structural metal shape which eliminates use of separate pipes and tubes in many cases and which can be readily rolled the same as other forms of structural metal in use today.

My invention consists, generally stated, in the novel arrangement and construction as hereinafter set forth and described and particularly pointed out in the appended claims.

To enable others skilled in the art to which my invention appertains to construct and use my improved structural metal shapes I will describe the same more fully referring to the accompanying drawings, in which:

Figure 1 is a front elevation of the rolls employed for forming the metal shape preparatory to finishing the conduit or tube. Fig. 2 is a like view showing the flange 35 turned to form one half of the conduit or tube but before the same is welded down. Fig. 3 is a like view showing the welding or securing of the flange end to the main part of the channel form there shown. Figs. 4, 40 5, and 6 are cross sectional views of a channel showing the process of forming the intermediate flange into the outer half of a conduit or tube. Fig. 7 is a side view of a channel shape showing the manner of connecting the different lengths together. Fig. 45 8 is a view of the channel shape showing how a connection can be made at any point of the shape with the conduit or tube. Fig. 9 is a cross sectional view of the same on the lines 9-9 of Fig. 8. Fig. 10 is a side view of a channel shape showing another method of connection with the conduit or tube at any desired point. Fig. 11 is a cross sectional view of the same on the lines 11-11 55 of Fig. 10.

Like symbols of reference herein indicate

like parts in each of the figures of the drawings.

My improved structural metal form or shape is intended to eliminate the use of 60 separate pipes and conduits and their necessary supporting members and can be embodied in any forms such as angles, beams, channels, plates, etc., and although I have shown a channel form embodying my invention 65 I do not desire to limit myself to that or any other particular shape.

In the drawings (Figs. 1 to 3) I have only shown the rolling from the time the metal has been formed into channel shape 70 up to the point of my invention as I have deemed it unnecessary to show the ordinary "breaking down" from billet form to the finished channel shape as this is well known in this art. Therefore, Fig. 1 is intended to 75 illustrate the first pass through the rolls after the metal has been rolled to finished shape in cases where a regular channel is being formed.

As illustrated in the drawings 1 represents 80 the lower rolls and 1' represents the upper roll of the first pass. In the first pass shown the channel shape 2 having the end flanges 3 is being provided with a semi-circular groove or depression 4 and a flange 85 5, one side of which coincides with one side or inner edge of the said groove or depression 4. The groove 4 is formed by means of the portion 4' of the upper roll 1' while the flange 5 is formed by means of the slot 6 90 in said roll. The shape 2 is also provided with a shoulder 7 having its one side or edge coinciding with that side of the groove 4 opposite the flange 5 while the outer half of 95 said shoulder has a rib 8 extending the entire length of the same. This shoulder 7 and rib 8 are formed by the faces 9 and 10 of the upper roll 1' and their purpose is described hereinafter. The outer face of the 100 shape 2 is provided with a reinforcing portion 11 which is formed by means of the depression 12 in the lower roll 1 and said portion is for the purpose of strengthening the 105 said shape at the point where the groove 4 is placed. When the shape has been thus formed as described above it is ready for the next pass where the lower roll 1 is identical with the lower roll of the preceding pass while the upper roll 13 is provided with a concave portion 14 for folding the flange 5 110 onto the shoulder 7 where it rests on the upper face of the rib 8 and such roll is also

provided with the flat face 15 for flattening the upper face 16 of the thus extended flange 5. The concave portion 14 of the roll 13 will, during the folding of the flange 5, considerably increase the length of the same so that there will be sufficient metal to extend entirely above the rib 8 as shown in Figs. 2 and 3. However, the length of the flange 5 will depend entirely upon the amount that it is extended by the folding over onto the shoulder 7 and the depth of the slot 6 can be regulated accordingly. When the flange 5 is thus turned over onto the shoulder 7 the conduit 17 will be formed the entire 15 length of the shape 2 and the finishing thereof depends upon the last pass or passes of rolls and whether or not it is necessary to put the metal through more than one pass will depend entirely upon experiments 20 which will be performed to determine this particular. In the last pass the roll 1 employed is identical with the lower roll used in the two described passes but the upper roll 18 is provided with a flange 19 which 25 presses the metal of the flange 5 onto the inner half of the shoulder 7 and thus completely welds the same thereto. This welding operation may require two passes through the rolls and may require being reheated before the parts are securely welded together but experiments will determine 30 both of these essentials.

In Fig. 7 I have shown a method of connecting the conduits 17 of several sections 35 together or of connecting a separate conduit to the end of the conduit 17 as desired, it being only necessary to tap threads 29 in the end of said conduit and either insert a pipe or inner coupling 21.

40 In Figs. 8 and 9 I have illustrated a method of drilling and tapping into the conduit 17 at any point desired and inserting a coupling 21 to which any desired connection can be made.

45 In Figs. 10 and 11 I have shown another method of connecting the conduit 17 at any point desired by merely removing a portion of the base of the shape 2 to form the opening 22. The open ends of the conduit 50 bordering on the opening 22 may be tapped

and a coupling 21 screwed into each side thereof and far enough therein to permit a T joint 23 to be inserted and connected with said couplings. This would require sufficient threading in the conduit to screw at 55 least one of the couplings 21 almost entirely into the conduit, in order to insert the T whereupon the coupling would again have to be screwed outward to unite with the T.

It will readily be seen that with the use 60 of my improved structural metal form a great amount of pipe fitting will be saved and connections can readily be made at any place required.

A preferred use of my improved structural metal shapes is for the bottom of railroad cars and such metal may be formed into any shape and the conduit used for carrying the compressed air for braking the speed of the car thereby eliminating the 70 use of separate pipes and their necessary connections. My invention may also be used in building construction and the conduit 17 used to contain wires, etc., or the conduit may be used for carrying water, 75 steam or other fluids.

Various modifications and changes in the design, construction and application of my improved structural metal shapes within the scope of the appended claims may be re- 80 sorted to without departing from the spirit of the invention or sacrificing any of its advantages.

What I claim as my invention and desire to secure by Letters Patent is:

1. A structural shape having a groove 85 rolled therein, and an integral bendable flange adapted to cover said groove.

2. A structural shape having a groove rolled therein, and an integral bendable 90 flange adapted to cover said groove, the outer edge of said bent flange being riveted to said structural shape.

In testimony whereof, I have hereunto set my hand.

ADAM A. VEBELUNAS.
